(57) **CLAIM**

The ornamental design for a bottle, as shown and described.

DESCRIPTION

FIG. 1 is a perspective view of a bottle, showing the front, the left side, and the top of our new design;

FIG. 2 is an elevational view of the front of the bottle;

FIG. 3 is an elevational view of the back of the bottle;

FIG. 4 is an elevational view of the right side of the bottle;

FIG. 5 is an elevational view of the left side of the bottle;

FIG. 6 is a plan view of the top of the bottle; and,

FIG. 7 is a plan view of the bottom of the bottle.

In FIG. 1, a closure is shown in broken lines, installed on the bottom of the bottle; this is shown solely for purposes of illustration and is not included in the claimed design.
